UNITED STATES PATENT OFFICE.

WILLIAM G. SHIPWRIGHT AND FRANK R. MARTIN, OF LONDON, ENGLAND.

FLOOR FOR BUILDINGS.

1,286,128.

Specification of Letters Patent. Patented Nov. 26, 1918.

Application filed June 15, 1915. Serial No. 34,255.

To all whom it may concern:

Be it known that we, WILLIAM GEORGE SHIPWRIGHT, and FRANK REGINALD MARTIN, subjects of the King of Great Britain and 5 Ireland, residing at London, England, have invented new and useful Improvements in and Relating to Floors for Buildings, of which the following is a specification.

This invention has reference to improvements in and relating to floors for buildings, more particularly floors of the type built up of beams made of a plurality of bricks or blocks connected to each other by tie-rods, and cement or reinforced concrete, without 15 employing any temporary supports.

Our invention consists in a floor construction in which tile-beams constructed as hereinafter described are mounted parallel to each other some distance apart on the 20 girders or the like which support the floor, shallow tiles are fitted in the bottom of the space between adjacent beams, and the said spaces are then filled in with concrete which becomes keyed in dovetail grooves formed 25 in the sloping sides of the beams.

The burnt-clay or like blocks or tiles which we employ in constructing the beams are of approximately inverted V or trapezoidal or arched cross-section, and consequently, when a number of these bricks or 30 tiles are arranged end-to-end and connected to each other by means of metal rods or bars embedded in cement in longitudinal grooves in the tiles to form a beam or slab, and when 35 two of these beams or slabs are placed side by side, an approximately V-shaped space is formed between the said beams. The V-shaped spaces between the beams are intended to be filled in with concrete or reinforced concrete after the beams or slabs are 40 placed in position on the girders which are to support the floor, and we form dovetail grooves in the sloping sides of the tiles for the purpose of forming a perfect joint between the concrete and the tiles by the concrete becoming keyed in the said grooves.

The mass of concrete keyed in the wedge or trough-shaped spaces between the tile-beams offers a resistance to compressional 45 strains which is approximately proportionate throughout the whole section and consequently theoretically perfect. The dovetail grooves may run lengthwise of the beams or in any desired direction. Similar 50 dovetail grooves may be formed on the underside of the tiles when a plaster or like

ceiling is to be applied thereto. The blocks or tiles may be hollow, for the purpose of lightening the construction and improving the fire and sound resisting properties of 60 the floor.

In addition to the dovetail grooves referred to, we form in the sloping sides of the tiles longitudinal grooves to receive tie-rods or bars; and in constructing a beam we arrange the required number of tiles in alignment end-to-end with their flat bases resting upon some flat surface, and then place the said rods or bars in the said grooves and fill in the grooves with cement or concrete. The 70 beams are ready for use as soon as the cement or concrete has set hard.

We have illustrated our invention in the accompanying drawing, in which:—

Figures 1 and 2 are perspective views of 75 two forms of blocks or tiles which we employ, Fig. 1 showing a tile of approximately inverted-V cross-section, and Fig. 2 a tile of arched cross-section;

Fig. 3 is an end view of a tile-beam built 80 up of tiles somewhat similar in shape to the one shown in Fig. 1 but of greater depth and with slightly concave sloping sides;

Fig. 4 a longitudinal section of part of 85 a finished floor; and

Fig. 5 is a cross section of our floor construction.

Referring to the drawing, the tiles A have sloping sides in which as well as in the flat bases of the tiles dovetail grooves *a* are 90 formed. A number of these tiles are arranged in alignment end-to-end, resting upon their flat bases, and connected to each other to form a beam or slab by embedding metal rods or bars B in cement, concrete or 95 the like in grooves *b* formed in their sloping sides and at the apex of the tiles. The beams are ready for use as soon as the cement has set hard in these grooves *b*. The tiles may be hollow as indicated in dotted lines in the 100 drawings.

The ends of the beams are supported on girders or the like as indicated at D in Fig. 4.

As shown in Fig. 5 the tile-beams are 105 spaced some distance apart and shallow tiles C are arranged in the bottom of the approximately trough-shaped space between adjacent beams before the said space is filled in with concrete, the said tiles being 110 adapted to fit between the beams so that they rest upon the sloping sides thereof. Rein-

forcing rods or the like may be embedded in the concrete if desired to give additional strength to the construction.

No wood centering or other temporary supports are required of course in constructing the floor, and if additional thickness is required it is only necessary to apply more concrete so that the wedge-shaped masses form a homogeneous whole with the additional concrete applied above the tiles.

What we claim as our invention and desire to secure by Letters Patent is:—

A floor construction in which beams that are built up of a plurality of tiles having lateral faces sloping upward toward each other at equal angles to their bases and which tiles are arranged end-to-end in alinement, connected to each other by metal rods embedded in cement in longitudinal grooves in the said

sloping faces, and formed with dovetail 20 grooves in the said faces are mounted parallel to each other some distance apart on the floor supports, shallow tiles shaped to fit between and rest upon the sloping sides of the beams are placed in the bottom of the trough-shaped spaces between adjacent beams, and the said trough-shaped spaces are filled in with concrete which becomes keyed in the aforesaid dovetail grooves. 25

In testimony whereof we have signed our 30 names to this specification in the presence of two subscribing witnesses.

WM. G. SHIPWRIGHT.
F. R. MARTIN.
